FLORENCE BOLTON, OF BERKELEY, CALIFORNIA, ASSIGNOR TO WILLIAM ELLERY, OF SAN FRANCISCO, CALIFORNIA.

WOMAN'S OUTING-SUIT.

Specification of Letters Patent.

Patented Oct. 21, 1913.

Application filed May 21, 1912. Serial No. 698,681.

To all whom it may concern:

Be it known that I, FLORENCE BOLTON, a citizen of the United States, residing at Berkeley, in the county of Alameda and State of California, have invented new and useful Improvements in Women's Outing-Suits, of which the following is a specification.

This invention relates to improvements in women's suits, and has for its object to provide a complete suit, made in one piece, adapted for various forms of outdoor activity, which will permit complete freedom of movement of the body and limbs, which, by reducing the number of garments usually worn, will avoid the heat, weight, and general discomfort heretofore occasioned by such garments, and the time and trouble necessitated in putting them on and off, and will also avoid constriction and fullness of the clothing about the waist and hips.

In the accompanying drawing, Figure 1 is a front view of the garment, as used for ordinary walking; Fig. 2 is a rear view of the same; Fig. 3 is a front view as used for riding astride, or when greater freedom of movement of the legs is required; Fig. 4 is a front view of the garment in its open or unfastened condition.

My improved suit may be made in two forms, either complete in one piece from the neck, or sleeveless and low cut, to be worn with a separate guimpe or shirt. In both cases it is cut to hang from the shoulders, and is half fitting, and beltless, or has merely a simulated belt. Since the difference in the two forms is immaterial to the invention, I shall show only the latter form thereof.

The suit consists of the following parts, secured together to form a one-piece garment: 5 indicates front and rear crotch pieces connected to one another at their inner edges and which cover the inner portions of the legs, and the lower portion of the body both at front and rear, but not at the sides. These crotch pieces do not extend above the waist of the wearer. 2 indicates side pieces which extend the full length of the garment, and each of which comprises a waist portion 1 and a skirt portion 3. These side pieces cover the sides of the body, and the outer sides of the legs, and the outer edges of the crotch pieces are secured to the lower portions of the edges of said side pieces. Thus the lower portions of the side pieces form, with the crotch pieces, a bifurcated skirt. 7, 8, indicate front and rear wide gores or panels, each of which extends from the top to the bottom of the suit. 60 They are attached at their edges to the respective side pieces and complete the suit by covering the upper portion of the body above the waist line both at the front and rear. The lower portions of these panels 65 cover the bifurcations at the front and rear, when desired. Both panels 7, 8, are permanently secured to the remainder of the garment along one edge only for the greater part of the length of said edge, the lower 70 portion of said edge, however, being free, and the other edge being detachably secured as hereinafter described. Each side of each panel, from the waist line down is formed with an extra plait 9, which, as 75 shown at 11, is stitched down near the outer edge to within a short distance above the knee, but is left open or unstitched in the lower portion, as shown at 12, in order to give greater freedom of movement to the 80 limbs.

The garment is detachably closed or fastened at the front by hooking a series of hooks 13 to a corresponding series of eyes 14, said hooks and eyes being secured respectively to adjacent edges of the upper halves, or thereabout, of the skirt portion of the suit, and of the adjacent crotch piece 5. Above the waist line, the garment is detachably closed at the front by means of 85 eyes 16 on the waist and corresponding hooks 17 upon the adjacent edge of the front gore or panel 7. When it is desired to use the garment closed either at the front or rear lower portion or both then the lower portion of the corresponding gore is also secured to the lower portions of the garment by means of hooks 18 on the edge of said gore which engage eyes 19 on the outer side of the marginal portion of the 90 corresponding crotch piece. When complete freedom of movement of the legs is desired, the hooks 18 are disengaged from the eyes 19, as shown in Fig. 3.

I claim:—

1. In a woman's one-piece outing suit, the combination of front and rear crotch pieces connected together at their inner edges and suitably shaped to cover only the inner sides of the legs and the front and rear portions 110

- of the body below the waist line, side pieces, each shaped to cover only the sides of the body above and below the waist and the outer sides of the legs, said side pieces, below the waist, being connected with the crotch pieces to form a bifurcated skirt, a front panel the edges of which are connected to the front edges of the side pieces above and below the waist line, and a rear panel the edges of which are similarly connected with the rear edges of the side pieces, one edge of one panel being detachable from the corresponding edge of the corresponding side piece.
- 15 2. In a woman's one-piece outing suit, the combination of front and rear crotch pieces connected together at their inner edges and suitably shaped to cover only the inner sides of the legs and the front and rear portions of the body below the waist line, side pieces, each shaped to cover only the sides of the body above and below the waist and the outer sides of the legs, said side pieces, below the waist, being connected with the crotch pieces to form a bifurcated skirt, but said connection of an upper portion of a crotch piece being on one side detachable, a front panel the edges of which are connected to the front edges of the side pieces above and below the waist line, and a rear panel the edges of which are similarly connected with the rear edges of the side pieces, one edge of one panel being detachable from the corresponding edge of the corresponding side piece.

3. In a woman's one-piece suit, the combination of an outer portion made of a single thickness of cloth, and of a shape to surround the trunk and the legs of the wearer, and a crotch portion of a shape to cover only the inner sides of the legs and the front and rear of the trunk below the waist line, and connected along its upwardly extending edges to the outer portion, the lower part of said outer portion being separable edges both at front and rear to permit the garment to be used as a bifurcated skirt, and co-engaging fastening devices on said separable edges for uniting them to form an ordinary skirt.

In testimony whereof I have hereunto set my hand in the presence of two subscribing witnesses.
